(57) **CLAIM**

The ornamental design for a table lamp, as shown.

DESCRIPTION

FIG. 1 is a view of the front (the white part) of the lamp, but is also showing a bit of its left side. Left side of the lamp, is equal to the lamps right side and the bottom of the lamp.

FIG. 2 is as FIG. 1, but showing a bit more of the lamps left side.

FIG. 3 is a view of the left side of the lamp, showing the angle and tourment of the lamp; and,

FIG. 4 is a view of the back of the lamp, seen from the right side of the lamp.
